Wm. J. Brinkley
ATTORNEY

UNITED STATES PATENT OFFICE.

LOUIS BARNETT, OF NEW YORK, N. Y.

PLUG CAP.

Application filed March 26, 1925. Serial No. 18,360.

This invention relates to attachment fittings for electric circuits and more particularly is directed to improvements in the cap portion of two-piece, separable, electrical attachment plugs for connecting portable appliances, lighting systems and the like apparatus to an electric power source.

An object of the invention is the provision of an improved attachment plug-cap of the character described which shall be constructed of few and simple parts, cheap to manufacture and practical and efficient to a high degree.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention,

Fig. 1 is a sectional view of an attachment plug-cap embodying the invention, showing one practical application of the invention in connecting a plurality of circuits to one power source;

Fig. 2 is a plan view of the attachment plug-cap shown in Fig. 1;

Fig. 3 is a sectional view taken on lines 3-3 in Fig. 2; and

Fig. 4 is an elevational view of a modified form of the plug-cap embodying the invention having a compactly shaped body portion.

Referring in detail to the drawing, 10 denotes a plug-cap embodying the invention adapted to be inserted into a baseboard, flush-receptacle or fixture socket outlet (not shown) in the well known manner. The plug-cap 10 may comprise a body portion 11 formed of insulating material such as porcelain, "bakelite," or other like suitable substance and metallic current carrying portions 12. The latter may be secured in any suitable manner to the insulating body portion 11 as by means of metallic eyelet-anchors 13 which are preferably molded into the body portion as shown in Fig. 3. The current carrying portions 12 may comprise terminal blades 14 extending outwardly

from one side of the body portion 11 and spring contacting members 15 of any suitable construction extending into the socket portions or passage openings 11^a provided in the body portion. The terminal blades 14 and the contact members 15 are formed with flat extensions 14^a and 15^a respectively whereby they are firmly secured to the body portion 11 by means of said eyelet anchors 13. Each terminal blade 14 with its corresponding contact member 15 is thus united into a substantial unitary or integral structure. The contact members 15 extend only partially into the opening 11^a eliminating possible short circuits or injury to persons handling the device. If desired, each member 15 may be provided with a spring protuberance 15^b adjacent the extension 15^a for releasably engaging with an opening 14^b in the terminal blade 14. Binding screws 16 are provided for securing the ends of a conductor wire 17 to the terminal extension 14^a as shown in Fig. 1.

A dominant feature of the invention resides in the construction of the various parts of the plug-cap 10 and their relative arrangement which will now be described. As shown in Fig. 1, the passage opening 11^a and the contacting member 15 are disposed in angular relation with respect to the terminal blades 14. A through passage 11^b is provided in the body portion 11 and extends in angular relation to the said members 15 and blade 14 for connecting the conductor wires 17 to the current carrying portions 12. The interior of the body portion is preferably formed with a hollow or cavity 11^c for receiving the knotted ends 17^a of the conductor wires 17 thereby providing an efficient and practical strain relief for the conductor wire connections to the binding screws 16.

In fact, where a plurality of circuits such as standard Christmas tree lighting units and the like electrical appliances are to be connected to one supply source, this cap is particularly useful since it provides a quick means for adding one or more such units with the caps arranged in a most inconspicuous and convenient manner. Another advantage following from the angular relation of one cap with its contiguous cap and of the parts of the cap to the body thereof is that a normal outward pull on the connecting wires will not be transmitted

to the separable current carrying parts, thus minimizing the possibility of accidental disconnection of a circuit.

In using the invention, the attachment 5 plug-cap 10 is connected to the free ends of the conductor wires 12 through which electric power is to be supplied to an appliance, lighting device, etc. (not shown) and the terminal blades 14 of said plug cap are 10 inserted into a receptacle power outlet in the well known manner. Other apparatus may successively be connected in circuit by simply plugging in the terminal blades 14 of its plug-cap into the socket openings 11^a 15 of the plug cap already connected in circuit to contact with the members 15 as shown in Fig. 1.

From the drawing and description given above, it is seen that plug-cap 10 is of simple 20 construction and permits connecting a circuit to the power supply from a side away from the receiving or socket end thereof, so that another plug-cap may be connected in at the socket end without in any way 25 interfering with the conductor wires 17 thereof.

It will also be noted that by reason of the novel relative arrangement and construction of the parts of the cap, a series of plug 30 caps 10 can be arranged either in a cluster about the first plug-cap as shown in Fig. 1 or may be extended rearwardly of the first plug-cap by inserting the second one into the first in 180° angular relation to its position shown in Fig. 1.

It will thus be seen that there is provided 35 a device in which the several objects of this invention are achieved and which is well adapted to meet the conditions of practical 40 use.

As various possible embodiments might be

made of the above invention, and as various changes might be made in the embodiment above set forth, it is to be understood 45 that all matter herein set forth or shown in the accompanying drawing is to be interpreted as illustrative and not in a limiting sense.

Having thus described my invention, I claim as new and desire to secure by Letters 50 Patent:—

1. A plug-cap of the character described comprising an insulated body portion having socket openings, and current carrying portions secured to the body portion, said current carrying portions including spring contact members extending within said socket openings and terminal blades projecting from one side of said body portion at a greater than 90-degree angular relation to said contact members, said body portion having a passage extending intermediate said contact members and blades, said passage being adapted to receive a conductor wire for connecting a parallel circuit to the 60 current carrying portions of the plug-cap.

2. A plug-cap of the character described comprising an insulated body having two flat face portions inclined at an angle with respect to each other, one of said face portions having socket openings extending perpendicularly thereto into the body, current carrying means consisting of spring contact members positioned in said openings, and terminal blades projecting outwardly from the other of said face portions, said body having an outlet passage between said face portion communicating with the inner ends of said socket openings, as and for the purpose described and specified.

In testimony whereof I affix my signature.
LOUIS BARNETT.
